CLAIM

The ornamental design for an automobile engine controller cover, as shown and described.

DESCRIPTION

FIG. 1 is a front elevational view of the automobile engine controller cover;

FIG. 2 is a rear elevational view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front, right-side, top perspective view thereof;

FIG. 8 is a front, right-side, top perspective view thereof;

FIG. 9 is a front, left-side, top perspective view thereof;

FIG. 10 is a cross-sectional view thereof taken along line 10-10 in FIG. 1;

FIG. 11 is a cross-sectional view thereof taken along line 11-11 in FIG. 1;

FIG. 12 is an enlarged view of area 12 in FIG. 10;

FIG. 13 is an enlarged view of area 13 in FIG. 10;

FIG. 14 is an enlarged view of area 14 in FIG. 11;

FIG. 15 is an enlarged view of area 15 in FIG. 11;

FIG. 16 is an enlarged view of area 16 in FIG. 8;

FIG. 17 is an enlarged view of area 17 in FIG. 8;

FIG. 18 is an enlarged view of area 18 in FIG. 9; and,

FIG. 19 is an enlarged view of area 19 in FIG. 9.

The broken lines depict either (i) portions of the controller cover that form no part of the claimed design, (ii) cross-sectional indication lines that form no part of the claimed design, or (iii) boundaries of enlargement areas that form no part of the claimed design. The dot-dash-chain lines depict boundaries of the claimed subject matter and form no part of the claimed design.
